PROPORTIONAL SPACING APPARATUS

Erik Frey and Russell E. Hattis, Chicago, Ill.

Application March 15, 1952, Serial No. 276,849

16 Claims. (Cl. 197—84)

1

This invention generally relates to typewriting machines and, more particularly this invention relates to proportional spacing apparatus for use with typewriting machines.

One object of this invention is to provide an improved spacing apparatus wherein the spacing produced is proportional to the size of the letter typed.

Another object of the instant invention is to provide a novel proportional spacing apparatus which may be used to readily convert conventional fixed spacing typewriters to proportional spacing typewriters.

Still another object of the instant invention is to provide a novel and improved proportional spacing apparatus which operates through electrical relays to move the carriage of a typewriter.

A further object of the instant invention is to provide a novel and improved apparatus which provides both proportional front and back spacing for a typewriter.

Another object of the instant invention is to provide a novel and improved variable spacing mechanism which also provides for adjustable line spreading in a typewriter.

A still further object of the instant invention is to provide a novel and simple switch mechanism for actuation by the character keys of a proportional spacing typewriter to energize electrical apparatus which controls the movement of the carriage which in turn controls the spacing between the printed letters.

Other objects of the instant invention will become apparent upon making reference to the specification which follows and the drawings wherein:

Figure 1 shows a side view of the apparatus of one embodiment of the instant invention added to a conventional fixed spacing typewriter;

Figure 2 is a rear view of a portion of the apparatus shown in Figure 1;

Figure 3 shows the switch actuating apparatus which is operated directly by the character keys of the typewriter of Figure 1;

Figure 4 shows a modification of the apparatus of Figure 3;

Figure 5 shows a sample wiring diagram for the operation of the relay mechanism shown in Figures 1 and 2;

Figure 6 shows a modification of the relay actuation mechanism shown in Figures 1 and 2;

Figure 7 shows an improvement over the relay mechanism shown in Figures 1 and 2;

Figure 8 is a view of a portion of the apparatus of Figure 7 in a different operating condition than there shown.

2

The description that follows will describe several embodiments of the instant invention as applied to the conversion of a conventional fixed spacing typewriter to a proportional spacing typewriter with a minimum of effort and expense. It should be understood however that the invention may be incorporated into a typewriter as manufactured. Also, numerous modifications may be made of the specific and preferred embodiments of the instant invention without deviating from the broader generic aspects of the instant invention.

In the drawings to be described, the parts of the conventional fixed spaced typewriter to which the invention is applied in the drawings have been omitted for purposes of simplification with only the outline thereof shown in dotted lines. The parts, which must be added to the conventional fixed spacing typewriter to adapt it for proportional spacing, are shown in solid lines. Also, like reference numerals in the several figures represent the same elements.

The conventional fixed spacing typewriter generally includes a rack fixed to the carriage and a pawl which normally engages the rack. The force for moving the carriage is generally provided by a spring which is placed under tension when the carriage is manually moved to its starting position. The pawl engages the rack until a character or spacing key is struck. Then the pawl is released from engagement with the rack momentarily which allows the carriage to move under the force of the spring at a fixed amount which is independent of the size of the letter struck. Such a typewriter also includes a lever which frees the rack of the carriage from engagement with the pawl above-mentioned. Then the carriage may be freely translated by hand. Such a lever will be hereinafter referred to as the carriage release lever.

Since all of these above elements are conventional and well known, the detailed description thereof has been omitted.

The present invention makes it possible to simply convert a fixed spacing typewriter to a proportional spacing typewriter which spaces the letters of a word an amount proportional to the size of the letters of the word. Thus, for example, when the character key printing the letter "i" is struck, the carriage will be moved, say, one unit; while when the character key printing the letter "w" is struck, the carriage will be moved, say, six units. Such a carriage action saves paper as well as providing printed matter having a much more desirable appearance.

There are numerous proportional spacing type-

writers in the prior art, but none have the simplicity of the instant invention which makes it possible to readily convert fixed spacing typewriters to proportional spacing typewriters. Also, the existing proportional spacing typewriters do not provide for automatic proportional back spacing or have adjustable line spreading features which are as simple and effective as the line spreading mechanism which is to be herein-after described.

One feature of the instant invention comprises mounting a rotatable feed screw on the frame portion of a fixed spacing typewriter and connecting an arm to the carriage which rides in the groove of the thread of the feed screw. A ratchet gear mechanism is connected to the end of the feed screw and is used to impart rotary motion to the screw. The ratchet mechanism is operated by an electromagnetic device which moves the ratchet mechanism an amount proportional to the energized condition of the electromagnet. The energization of the electromagnet is controlled by sets of electrical contacts which are actuated by the keys of the typewriter. The electromagnet may include a plurality of separate windings which when separately energized impart a different amount of motion to the ratchet gear mechanism. The carriage release lever above-mentioned is held in a depressed condition so that the position of the carriage is under the control of the feed screw. The particular windings which are energized is dependent upon the size of the letter just typed so that variable spacing is provided.

Referring now to the drawings, and Figures 1 and 2 in particular, one embodiment of the invention comprises a relay apparatus or electromagnet 13 having three separate windings which may be energized either separately or together in various combinations by the key mechanism (3, 4, etc.) of the typewriter 1. A switch unit 2 is placed under the key mechanism of typewriter 1. In the example shown in Figures 1 and 2, this switch unit includes six switch actuation strings or threads 11 which close respective switch contacts (not shown) connected to each thread when the threads are placed under tension. The threads are placed under tension when engaged by projections, such as 8, 10, and 10', depending from the arms of the character or spacing keys, such as 3 and 4, of the typewriter. Normally these projections do not engage the threads 11. When a particular character key is depressed, however, one or more of threads 11 are placed under tension, as shown in Figure 3, which closes one or more pairs of switch contacts associated therewith. The closing of a switch couples a suitable voltage source (such as the conventional A. C. line voltage) to one or more of the windings of electromagnet 13. The magnetic force developed in electromagnet 13 attracts a rack wheel actuation lever arm 14 an amount which is dependent on the windings energized. Lever arm 14, which pivots about a pin 17, includes an extension 15 made of a magnetic material which is attracted to electromagnet 13, thus pulling down the end of lever arm 14 an amount proportional to the magnetic force developed by electromagnet 13. Each winding of electromagnet 13 provides a different amount of force when energized. Pivoted to the end of lever arm 14 is a rack or pawl member 23 which includes an upper offset U-shaped portion including a first toothed portion 24 normally engaging a first gear 31 and a second toothed portion 26 on the 75

other side of gear 31 and axially displaced therefrom which is normally adjacent to but disengaged from a second ratchet gear 31'. Ratchet gears 31 and 31' are fixedly connected to a spiral lead screw 33 which is normally engaged by a carriage arm 22 riding in the spiral groove of lead screw 33. Screw 33 is rotatably supported in bearings such as 63 connected by brackets to the ends of the stationary frame portion 60 of the typewriter. Arm 22 extends from carriage 59 which carries the typing paper and moves across the front of the stationary frame portion 60 of the typewriter. As ratchet gears 31 and 31' are rotated by rack or pawl arms 24 and 26 respectively, the lead screw is rotated within bearings 63, etc.; and depending upon the direction of rotation thereof, the carriage arm 22 and carriage 59 may be moved in either the forward or backward direction. The carriage must, of course, be freed from engagement with the carriage rack pawl previously referred to. This is accomplished by keeping the carriage release lever 41 depressed. This may be accomplished by means of a screw 40 which is attached to the typewriter by a bracket 42 held in place by a nut 43 (see Figure 1).

The teeth of ratchet gear 31 are adapted to be rotated in a direction by rack arm 24 which will move the carriage 59 to the left as viewed from the front of typewriter 1 for forward spacing. Rack member 23 is normally held in an upper position by a spring 25 which operates against the force of electromagnet 13. Energization of electromagnet 13 by depression of a character or spacing key pulls down arm 14. As electromagnet 13 is de-energized as the operator lets go of the character key, spring 25 will pull rack arm 24 back into its normal position causing rotation of ratchet gear 31. Because of the shape of the teeth of the ratchet gear 31 and rack arm 21, the downward motion of rack 23 will not impart motion to wheel 31 to prevent any back spacing of carriage 59 when the character key is depressed. Only the upward motion of the rack will rotate gear 31. The amount of rotation of ratchet gear 31 is dependent upon the distance the lever arm 14 is pulled downward by electromagnet 13. Rack arm 26 and ratchet gear 31' operate in a similar manner to ratchet 31 and rack arm 24 just described. The direction of the extent of the gear teeth on gear 31' and rack arm 26 is reversed, however, to provide for back spacing. A lever 6 pivoted about point 28 is actuated by the back space key 5. Thus depression of back space key 5 depresses one end of lever 6 which causes the other end 29 thereof to be raised. Connected to the end 29 of lever 6 is a transverse rod 62 (shown in dotted lines in Figure 2 since it may not actually be seen from the back of the typewriter) which rides in a slot 27 in rack arm 26. As transverse rod 62 moves upward, it presses against the side of slot 27 thereby pivoting rack 23 about pivot point 19' at the end of lever arm 14. This action pushes rack arm 26 in engagement with ratchet gear 31' and disengages rack arm 24 from engagement with ratchet gear 31. Then when a character or spacing key, such as 3 or 4, is depressed, the electromagnet 13 is energized and lever arm 14 is pulled down an amount determined by the key pressed. Ratchet gear 31' is rotated in a counter-clockwise direction as viewed in Figure 1, as the character key is released which de-energizes electromagnet 13. This rotates screw 33 in a direction to move carriage 59 backwards for the

back spacing operation. The procedure for back spacing therefore is to hold the back space lever down with the finger of one hand and then to depress and release the character key which corresponds to the letter previously typed. This returns the carriage to the same position it was in before the last letter was typed.

In order to prevent the typing of a letter during the back spacing operation, an arm member 30 may be connected to transverse rod 62. A thin plate member 35 is attached to the end of arm member 30 so that as arm member 30 is raised with transverse rod 62, the plate member 35 is raised in front of the type bar (not shown). Plate member 35 slides behind type bar guide member 37 in the embodiment shown in Figure 1. If the typewriter has a "dead key" or mimeograph key mechanism which prevents the printing of a character as a key is struck, the back space key may be adapted to operate the "dead key" or mimeograph key mechanism.

Since the force of the relay provides the force for moving the carriage, if desired, the forward movement of the carriage may be used to store up energy in a conventional typewrite tape-spring apparatus comprising a cylindrical housing 57 and a flexible spring tape 58 which tends to wind itself within housing 57. The energy used to store up energy in the spring is used for the purpose of returning the carriage to its initial position. Thus, as the carriage moves to the right as viewed from the rear of the typewriter as seen in Figure 2, the spring 58 is unwound from housing 57 and is placed under tension much in the same manner as in conventional typewriters except that in such typewriters, the spring tension is used to aid the forward motion rather than the backward motion of the carriage. The position of such a spring apparatus in the more conventional typewriter need only be reversed in position to convert same into the typewriter machine shown in Figure 2.

As shown more clearly in Figure 1, a return key 44 is provided to raise the carriage arm 22 to disengage it from the carriage screw 33. Arm 22 swivels relative to an upper arm member 21 which is directly connected to carriage 59 as by a suitable bracket 21'. The upper arm member 21 is made to swivel relative to bracket 21' by means of any suitable means such as a nut-and-bolt arrangement 22"-51 passing through holes in the arm member 21 and bracket 21'. A similar nut-and-bolt arrangement may be used for the swivel connection between carriage arm member 22 and arm member 21. Carriage return key 44 is coupled to a lever 45 which pivots about a fixed shaft 47 so that a downward movement of key 44 produces an upward movement of the end 48 of lever 45. End portion 48 is connected to carriage arm 22 as by a screw 53 so that the depression of carriage return 44 raises arm 22 from engagement with screw 33 by a swivel motion.

To provide for line spreading, the point about which ratchet wheel actuation lever arm 14 pivots is made variable. For a given attractive force developed by electromagnet 13, the amount of movement of the free end of lever 14 depends upon the point about which lever 14 pivots. A bracket 13 is connected to frame portion 60 of typewriter 1 in any suitable manner and includes a plurality of threaded holes 65 in which a pin 17 may be threaded. Lever 14 has a slot 16 formed therein with a series of spaced rounded notched portions 16' in the top portion thereof which are placed opposite the threaded holes 75

in bracket 13. The edges of the slots rest on the top of pin 17 when placed adjacent thereto and lever 14 pivots about pin 17. If it is desired to spread a given line a small amount to even up the margin, then pin 17 is moved to the next notched position.

Refer now to Figure 3 which discloses the manner in which the relay energizing contacts are closed in response to depression of a character or spacing key. A thread 11 is shown suspended within container 2 shown in Figure 1 by means of suitable spacers 79, 80, etc. The other threads are similarly supported. When a character key 3 is depressed, the projection 10 presses downward on thread 11 putting it under tension so that contact 76 of normally opened contact pair 76-78 is effectively pulled into engagement with contact 78 thus completing an electrical circuit (shown in Figure 5) which energizes one of the windings of electromagnet 13.

Figure 4 shows an alternative but less preferred manner of closing the relay energizing contacts. In this embodiment, a separate bar 82 replaces each of the threads shown in Figures 1 and 3. As in the apparatus shown in Figure 3, each key is provided with projections such as 10 which actuate the particular bar placed beneath it which will actuate the desired windings of electromagnet 13. The bars may be held in a raised position by a spring such as 86 at each end thereof which extends upwardly from a spring housing such as 88 having a hole therein to receive the associated spring. Each bar includes an extension such as 84 carrying an electrical contact on the end thereof such as 87 which is normally held out of contact with another electrical contact such as 89 by the associated spring. Depression of a character or spacing key depresses the appropriate bar by means of the extension connected to the depressed key bar such as 9, and the electrical contacts operated by the particular bar are closed thereby energizing electromagnet 13.

Reference is now made to Figure 5 which shows the circuit diagram of the energizing circuit for electromagnet or relay 13. The three windings of electromagnet 13 are shown as windings 13a, 13b, and 13c, respectively. Each winding is coupled to a suitable voltage source through a connector plug 90 and contacts of various switches now to be described. First, however, it should be understood that, for the embodiment now described windings 13a, 13b, and 13c are composed of a different number of turns of wire so that energization of the respective windings produces a different amount of attractive magnetic force.

One of the six strings 11 actuates a different one of the six pairs of contacts 76-78, 76'-78', 92-94, 92'-94', 96-98, and 96'-98' in the manner shown in Figure 3. Thus each character key arm has one or more extensions such as 8, 10, and 10' (see Figure 1) overlying the string which it is to actuate. Where a given key bar does not have such an extension overlying a particular string, then depression of the character key associated with particular bar will not touch the said particular string.

Each relay or electromagnet winding may be connected to the energizing source by one of two paths. One path (the lower path in Figure 5) is rendered active when the lower case or non-shift letters or symbols are typed while the other path (the upper path denoted by the prime numbers in Figure 5) is rendered active when the shift key 3 (see Figure 1) is depressed. Where a given path is rendered active, the closing of the

pair of contacts actuated by the strings 11 will energize the associated electromagnetic winding but not otherwise (i. e., if it is not active). A ganged group of switches 100, 100', 102, 102', 104, and 104' are located in the same paths respectively as relay actuation switches 76-78, 18'-78', 92-94, 92'-94', 96-98, and 96'-98'. When the ganged switches are in their lowered position as shown in Figure 5, then the closing of the electromagnetic actuation switches in the lower path will have no effect but will have an effect in the upper path since then the electromagnetic windings have a complete path to the energizing voltage source through the electromagnetic actuation switches and the contacts of the ganged switches. The ganged switches are placed in this lower position by depression of the conventional shift key 4. (See Figure 1.) A projection 8 is soldered or otherwise connected to arm 7 of shift key 4 which depresses an arm 12' to which the ganged contacts are connected. The ganged switches are housed in any suitable housing 12 which is located in container 2 which, as previously stated, is placed beneath the keys of the typewriter. Ganged switches are normally held in an upward position by any suitable means such as a spring (not shown). Thus, different spacing may result by depression of a single key through operation of the shift key. Since the upper and lower case letters are usually of different width, this type of circuit is required for the embodiment shown in Figures 1-5.

If the separate energization of windings 13a, 13b, and 13c produces 1, 2, and 4 units of carriage movement, then 3, 5, 6, and 7 units of spacing may be accomplished by simultaneously energizing two or three windings in different combinations. In the embodiment shown in Figures 1-5, a minimum number of 6 pairs of contacts and 6 threads or bars 11 are needed for 3 to 7 spacing selections because the same contacts are actuated whether the upper or lower case letters of a given character key are selected. Figure 6 discloses a switching system which appreciably simplifies the number of components needed to effect the same results as the embodiment of Figures 1-5 where the typewriter is the type where the type bars are lowered rather than the carriage being raised to effect the typing of upper case or capital letters as in most present day machines.

In the embodiment shown in Figure 6, only three pairs of contacts are needed. Each pair controls the energization of one of the windings 13a, 13b, and 13c of electromagnet 13. The movable contacts 76, 92, and 96, respectively, are glued or otherwise connected to resilient arms 116, 116', and 116'', respectively, which normally hold the attached contacts displaced from the associated contacts 78, 94, and 98. The above elements are connected by any suitable means to a plate member 108 which may be connected to the type bar guide member 37. Type bar guide member 37 is found on most typewriters and includes a pair of guide arms 106 which engage and guide the arms (such as arm 120) to which the type bars (such as 110) which carry the raised type surfaces are connected. The resilient contact carrying arms 116, 116', and 116'' jut out into the general path of the type bars but are placed to avoid being struck by the side faces of the type except where projections extend from the side thereof. Thus, as shown in Figure 6, an upper group of projections 111, and 112 protruding from the side of a type bar 110 is shown pressing against contact carrying arm members 116 and 116'. This closes the pair of con-

acts 76 and 78, and 92 and 94 which, in turn, causes two of the windings 13a and 13b to be energized. If windings 13a and 13b individually cause 1 and 2 units respectively of carriage movement, then their combined energization causes a 3 unit movement of the carriage. The upper group of contacts control the energization of electromagnet 13 during the upper case or shift operation of the typewriter. During the non-shift operation, if the switches and type projections are suitably placed, the upper group of projections 111 and 112 are removed from contact with contact carrying arm members 116 and 116' and the lower group of type bar projections 113, 114, and 115 are moved into engagement with the contact carrying arm members 116, 116', and 116''. This simultaneously closes all of the contact pairs so that the maximum spacing results for the upper case letter typed during the shift operation. Of course, the number of projections in the upper and lower groups depends on the sizes respectively of the non-shift and shift (the upper and lower) characters.

The relay or electromagnet 13 shown in Figure 1, as previously stated, operates by providing different levels of magnetic force which accordingly move the lever arm member 14 and the ratchet mechanism associated therewith an amount proportional to this magnetic force.

Figure 7 discloses electromagnetic apparatus 169 of a slightly different character than that shown in Figures 1 and 2. In this apparatus the amount of movement imparted to the ratchet mechanism 23 is not necessarily related to the amount of magnetic force developed by the electromagnetic apparatus but, like Figure 1, is related to the energized "condition" of the apparatus. Thus, electromagnetic apparatus 160 consists of three windings 127, 131, and 134 which are energized by the depression of the character or spacing keys of a typewriter, either singly or in combination in the same manner as the three windings 13a, 13b, and 13c of electromagnet 13 in Figures 1 and 2. Thus, the same kind of switch devices shown in Figures 1-6 may be used with the apparatus shown in Figure 7. The windings 127, 131, and 134 are wound on separate coil forms 126, 130, and 133, respectively. Each coil unit is made movable with respect to the other to form separate distinct relay units 122, 123, and 124. The three units are mounted one next to the other about a common axis. Each relay unit includes a core movable relative to its associated winding. The cores of relays 123 and 124 move upward when the associated relay is energized and in so doing, bodily moves with it all of the relay units above it. This arrangement in effect provides for as many as seven distinct amounts of movement of lever 151 connected to the core of top relay 122. In the embodiment of Figures 1 and 2, a variation in line voltage used to energize windings 13a, 13b, and 13c of electromagnet 13 would vary the amount of movement of the carriage keeping all other conditions constant. This is not so with the apparatus shown in Figure 7.

A more detailed description of the operation and construction of the apparatus of Figure 7 will now be explained.

The top relay unit 122 includes windings 127 wound about a cylindrical core 126 made of any suitable insulating material. The movable core of relay 122 includes a cylindrical member 136 made of any suitable non-magnetic material and a magnetic member 140 cemented or other-

wise fixedly attached to cylindrical core member 136. Magnetic member 140 includes an annular upwardly projecting portion 161 which rides in the space between the outer surface of cylindrical core member 136 and the inner surface of the cylindrical coil form 126. The bottom of magnetic member 161 normally rests in a pocket or opening in the top portion of a cap member 146, the top portion of which abuts and supports the coil form 126, etc. of relay 122. When current is passed through windings 127 of relay 122, the magnetic core member 140 is attracted upwardly toward the main portion of coil form 122 into the position shown in Figure 8. An annular shoulder 162 is provided on magnetic member 140 to limit the upward motion of magnetic member 140 as it abuts the bottom of coil form 126. The amount of upward movement of magnetic member 140 caused by energization of relay 122 is determined by the initial distance between the top of shoulder 162 and the bottom of the coil form 126 against which it abuts when moved upwardly by the magnetic force of relay 122. Cylindrical core member 136 moves with magnetic member 140 and in so doing, raises an arm member 150 connected with it. One end 151' of lever 151, which pivots about a pin 152, is connected to arm member 150 so that an upward movement of end 151' causes a downward movement of the other end 151" of lever 151. The end 151" of lever 151 is coupled to rack member 23 in a manner to be described so that energization of relay 122 moves rack member 23 downward. The de-energization of the relay units cause rack 23 to move upwardly under the force of spring 25 to move the carriage in the same manner described in connection with the apparatus shown in Figures 1 and 2.

Cap member 146, it should be noted, does not move at all if only relay 122 is energized. The latter member is connected to the cylindrical core member 137 of the relay 123 which is just below relay 122. Energization of relay 123 results in an upward movement of cylindrical core member 137 in a manner similar to that described in connection with the movement of core member 136 of relay 122, which raises cap member 146 therewith. This raises the entire relay 122 with it. A magnetic member 141 similar to magnetic member 140 if fixedly connected to the bottom of core member 137 and normally rests in a pocket formed in a cap member 147 associated with relay 124. The distance from the annular shoulder 161 of magnetic member 141 to the bottom portion of coil form 138 (when relay 123 is de-energized) is made greater than the equivalent dimensions associated with the components of relay 122. Therefore when only relay 123 is energized, the core of relay 123 including elements 141, 137, and cap member 146 is raised a greater amount than the core of relay 122 when the latter relay is alone energized as before described. Since the entire relay 122 is raised with the core of relay 123, it can be seen that energization of relay 123 alone will raise end 151' of lever 151 a greater amount than if only relay 122 were energized thereby providing greater letter spacing.

If relays 122 and 123 were both energized together, then it should be clear that the amount of upward movement of end 151' of lever 151 will be equal to the sum of the effects of the individual core movements of relays 122 and 123. Relays 124 including cap member 147, cylindrical core member 138, and magnetic member 142 is similar to the structure and operation of the

analogous components of relays 122 and 123. Since no relay is located below relay 124, magnetic core member 142 of relay 124 normally (when relay 124 is de-energized) rests in the pocket of a stationary base member 148.

It is desired that the energization of relay 124 alone should result in a greater amount of movement of lever 151 than energization of either relays 122 or 123 alone. The distance 10 from the shoulder 155 to the bottom of the coil form 133 of relay 124 (when the latter relay is de-energized) is accordingly made greater than the analogous dimensions of relays 122 and 123.

Figure 7 shows the condition of the electro-magnetic apparatus 160 when only relay 124 is energized.

As long as the voltage applied to the relays 122, 123, and 124 is sufficiently large to pull the respective magnetic core members 140, 141, and 20 142 into abutting relation with the bottom of the associated coil forms, the apparatus will operate consistently and accurately.

Needless to say, the amount of movement of rack member 23 will be the sum of the individual 25 results of each relay unit.

The embodiment of Figure 7 includes novel line spreading apparatus incorporated into the spacing apparatus there shown. Thus, the point at which the bottom portion of rack member 23 30 connects with lever 151 is made variable with the amount of line spread desired. The closer this connection point is to the pivot point 152 of lever 150, the smaller the amount of downward motion results from a given upward motion of the relay apparatus. A slot 154 is formed in the end of lever 150 adjacent rack member 23 and a bolt 153 or other suitable adjustable connecting means passes through slot 154 and a hole in the lower portion 156 of rack member 23 and 40 is held in place by a nut (not shown) threaded to the other end of bolt 153. The friction of the head of bolt 153 against the surface of lever 151 when the nut connected thereto is tightened sufficiently to prevent sliding of the bolt 153 is slot 154. Rack member 23 is, however, able to 45 rotate a little about bolt 153 as lever 151 is moved above pivot point 152. Lower portion 156 of rack member 23 is pivoted to the upper portion thereof by means of a suitable pivot joint 156' so that the portion of rack member 23 carrying the 50 toothed portions can freely slide between vertical guides 15. The motion of the toothed portion of rack member 23 is therefore a linear motion.

As previously stated, many modifications may be made of the preferred forms of the instant invention above described without deviating from the spirit and broader scope of the instant invention.

For example, electronic switches could be substituted for the mechanical switch arrangement 60 shown in Figure 6. In such case, each of the projections on the type bar 170 could be replaced by a small light source (broadly taken), such as a small circular area of white paint which reflects more light than the adjacent type bar surface or a small area of radium paint. The mechanical switches could each be replaced by a phototube or other suitable light detector which energizes one of the relay windings as the light source moves adjacent the phototube.

Although the back spacing system shown in Figures 1 and 2 is especially suitable for an electrically proportional spacing typewriter as there shown, it could be adapted with advantage 70 to even mechanically proportional spacing appa-

11

atus where rack member 23 is mechanically rather than electrically moved.

There are numerous ways to ensure that the lead screw 33 will always be in a position to return to a rotary position such that the carriage arm 22 will engage the lead screw slot when the carriage is at the left hand margin position. For example, the shaft could be spring biased in such a manner that when arm 22 is raised from the lead screw (the friction between the arm 22 and the screw could be made sufficiently to prevent rotation of the screw by the biasing spring), the said screw is free to rotate a small amount under the force of the spring to a fixed predetermined position. Since such a spring-biased shaft arrangement is obviously old in the art (for example, such an arrangement is found in the cylinders supporting the common draw shade), it is felt unnecessary to describe the details of such a spring biasing arrangement.

The instant invention thus provides a new and improved proportional spacing device which is relatively simple and inexpensive to use and which is especially adaptable for use in converting fixed spacing typewriters to variable spacing typewriters.

We claim:

1. In combination with the carriage and key mechanism of a typewriter, a gear means coupled to said carriage to move same a distance proportional to the movement thereof, a rack member having first and second toothed portions extending on opposite sides of said gear means for an engagement with the teeth thereof to move said gear means, said toothed portions of said rack member being spaced to allow engagement of only one toothed portion at a time with said gear means, said first toothed portion normally in engagement with said gear means during forward movement of said carriage, means actuated by the back space key mechanism of said typewriter to move said first toothed portion of said rack member out of engagement with said gear means and to simultaneously move said second toothed portion thereof into engagement with said gear means, rack actuation means coupled between the character key mechanism of said typewriter and said rack member to move the toothed portions thereof an amount proportional to the size of the letter printed by the particular key struck, and letter blanking means actuated by the back space key for preventing the printing of any letters as a character key mechanism is operated during a back spacing operation.

2. The combination of claim 1 characterized further by said gear means coupled to said carriage through a fixed feed screw rotated directly thereby and a feed screw thread engaging arm extending from the carriage to abut the sides of the feed screw threads and be moved thereby as said feed screw is rotated.

3. The combination of claim 2 characterized further by lever means for raising said thread engaging arm from said feed screw to allow said carriage to return to its starting position.

4. The combination of claim 1 characterized further by said letter blanking means comprising a flat plate member movable by the back space key mechanism into the path of the type bar to prevent same from striking the typewriter paper.

5. The combination of claim 1 characterized further by said rack actuation means comprising: an electromagnet for imparting rotation to said rack member, a source of electrical energy for

12

said electromagnet, and electric contact means coupled between said source of electrical energy and electromagnet and actuated by the character key mechanism of said typewriter to energize said magnet to a degree proportional to the desired spacing, said rack member being in cooperative relation with said electromagnet so as to be movable an amount proportional to the degree of energization of said electromagnet.

6. The combination of claim 5 characterized further by said electrical contacts being mounted on an insulating support member mounted adjacent the type bar guide member, said contacts being mounted for actuation by projections on the side faces of the type bar.

7. The combination of claim 1 characterized further by said gear means comprising first and second ratchet wheels mounted on a common shaft and having teeth of opposite type for rotation in opposite directions when engaged by the first and second toothed portions of said rack member, said first toothed portion of said rack member mounted adjacent one of said ratchet wheels and the said second toothed portion mounted adjacent said other ratchet wheel.

8. In combination with the carriage and character key mechanism of a typewriter, proportional spacing apparatus comprising an electromagnetic means for imparting motion to said carriage, ratchet mechanism including a rotatable ratchet wheel and a pawl means spring biased for rotating said ratchet wheel in only a first direction, said pawl means being movable by said electromagnetic means to a degree proportional to the degree of energization thereof, electrical contacts mounted for actuation by the character key mechanism of said typewriter for selecting the level of energization of said electromagnetic means, and means converting the rotary motion of said ratchet wheel to longitudinal motion of said carriage.

9. In combination with the carriage and character key mechanism of a typewriter, proportional spacing apparatus comprising electromagnetic means for developing a selectively variable attractive force, first means including a portion made of a magnetic material mounted for movement in an amount determined by the magnitude of magnetic force of said electromagnetic means, second means for coupling the motion of said first means to said carriage, and third means actuated by the character key mechanism of said typewriter for causing said electromagnetic means to develop a magnetic force proportional to the width of the character struck.

10. Apparatus for converting a fixed spacing typewriter having a carriage, character keys, and a carriage release key to a proportional spacing typewriter comprising a box beneath said typewriter containing a plurality of oblong switch actuation members extending transversely of and beneath the character key arms of said fixed spacing typewriter and respective electrical contacts coupled to said switch actuation members for actuation thereby, a spiral threaded screw rotatably mounted to the stationary frame of said fixed spacing typewriter; an arm extending from the carriage of said typewriter and engaging the sides of the threads of said screw for movement in response to rotation of said spiral screw; electromagnetic means adapted to be energized to a plurality of different conditions for moving said carriage varying amounts; means for coupling said electrical contacts between said electromagnetic means and a source of energizing volt-

age; the condition of said electromagnetic means determined by the selection of the contacts to be actuated by said switch actuation members; said character key arms including portions which abut the particular switch actuation members upon depression of said key arms to produce the desired condition of said electromagnetic means; lever means including a toothed portion on the end thereof mounted for movement by said electromagnetic means an amount variable with the energization condition of said electromagnetic means; and gear means coupled to said spiral screw for rotating same and mounted for engagement with and rotation by the toothed portion of said lever means in an amount varying with the amount of movement of said lever means.

11. The combination of claim 8 characterized further by said electrical contacts mounted on an insulating supporting member adjacent the said carriage of the typewriter, said electrical contacts comprising a plurality of normally opened pairs of contacts having projecting portions extending into the path of movement of the type bars of the typewriter, and projections on the side of the type bars of said typewriter for abutting the projecting portions of the contact pairs producing the desired letter spacing.

12. In combination with the carriage, type bars and type bar guide member of a typewriter, proportional spacing apparatus comprising a plurality of space selecting elements for moving said carriage different amounts after the typing of a letter, a plurality of electric contact pairs for connecting a source of energizing voltage to said space selecting elements mounted adjacent said type guide member, said contact pairs each having a projecting portion extending into the general path of movement of the said type bars for actuating the associated contact pair when engaged by a projection on said type bars, and projections on said type bars positioned for engagement with the appropriate projecting portion of said contact pairs to select the proper space selecting element for energization depending on the width of the letter just typed.

13. In combination with the carriage and type bars of a typewriter having two characters printable by the depression of a single character key by means of a shift key mechanism which varies the vertical position of the type bars, proportional spacing apparatus comprising a plurality of space selecting elements for moving said carriage different amounts after the typing of a letter, a plurality of electric contact pairs for connecting a source of energizing voltage to said space selecting elements, said contact pairs each having a projecting portion extending into the general path of movement of the said type bars for actuating the associated contact pair when engaged by a projection on said type bar, and two vertically spaced groups of projections on said type bars for engagement with the appropriate projecting portions of said contact pairs respectively only during shift and non-shift operation of the type-

writer to select the proper space selecting elements for energization depending on the width of the letter just typed.

14. In combination with the carriage and character key mechanism of a typewriter, proportional spacing apparatus comprising a plurality of axially displaced, contiguous coaxial electrical relay coils mounted for movement along their common axis, a separate core in each relay axially movable a fixed amount in the same direction relative to its associated coil as same is energized, respective means associated with the coils of the said relay coils for bodily moving the next successive relay coil and its core simultaneously with movement thereof, linkage means coupled to the core of the last successive relay for moving said carriage an amount proportional to the total displacement thereof, respective electrical contacts connected to said respective relay coils for connecting a source of voltage thereto to energize same, and means responsive to depression of said character key mechanism to actuate the particular electrical contacts which will cause a movement of said carriage proportional to the width of the letter just typed.

15. The combination of claim 14 characterized further by said linkage means including a pivoted lever coupled to the core of the said last relay, the distance of the free end thereof from the point of pivot being gradually variable whereby variable line spreading is provided.

16. In combination with the carriage and key mechanism of a typewriter, variable spacing apparatus comprising electromagnetic means for developing a force to move said carriage, a plurality of pairs of electrical contacts for coupling a source of energizing voltage to said electromagnetic means to vary the energization thereof, as determined by the particular pairs of contacts which are closed, means actuated by the character keys of said typewriter for closing the particular electrical contact pairs which will develop a level of energization in said electromagnetic means proportional to the width of the character struck, and means including a lever pivoted intermediate its ends with one end coupled to said carriage, said lever being movable an amount proportional to the degree of energization of said electromagnetic means to move said carriage a distance proportional to the width of a letter just typed, the distance between the end of said lever coupled to said carriage and the point of pivot of the lever being variable whereby line spreading is provided.

55 ERIK FREY.
